UNITED STATES PATENT OFFICE.

KINIAS M. JAFFERIAN, OF NEW YORK, N. Y.

DESIGN FOR A DOLL.

52,798.

Specification for Design. Patented Dec. 24, 1918.

Application filed March 4, 1918. Serial No. 220,405. Term of patent 3½ years.

To all whom it may concern:

Be it known that I, KINIAS M. JAFFERIAN, a subject of the Sultan of Turkey, residing at the city of New York, in the county of New York and State of New York, have invented a new, original, and ornamental Design for Dolls, of which the following is a specification, reference being had to the accompanying drawing, forming a part thereof.

The figure is a front elevation of a doll showing my new design.

I claim:

The ornamental design for a doll, as shown.

Signed at the city of New York, county of New York, and State of New York, this 2nd day of March, 1918.

KINIAS M. JAFFERIAN.
